COLLAPSIBLE FRAME FOR A SHELTER

James H. Turner, Detroit, Mich.

Application December 9, 1954, Serial No. 474,209

3 Claims. (Cl. 135—4)

This invention relates to a collapsible framework for a shelter of the tent type. The framework is adapted to support the canvas of the tent.

The invention resides in the collapsible framework and particularly in that portion of it embodied in an upper corner which includes adjacent side walls and the adjacent portion of the roof.

An object is to provide a collapsible framework of the character described which may be readily erected or readily torn down and disassembled and wherein the separate structural parts are so fabricated and fastened together that the complete framework may be disassembled into a minimum number of structural subassemblies.

A complete structural assembly comprises a plurality of subassemblies and parts which may be fastened together in a minimum amount of time to erect the framework and which may be disassembled quickly to disassemble the framework for packing, storing and transportation.

More particularly, the invention resides primarily in that portion of the framework which resides in one of the upper corners adjacent to the roof and which includes part of the frame of the adjacent side walls and the roof structure itself. This framework corner section is so constructed that the upright and lateral sections and the rafters of the roof may be swung into alignment with each other for storing and transportation. For erection these parts may be swung to the position they will assume in the erected structure and they retain such erect position when the assembly is complete.

The framework is simple and inexpensive and adapted for ease of assembly and disassembly. It is of light weight and occupies a minimum amount of space and presents an attractive appearance.

The collapsible corner section which forms a dominant feature of the assembly is embodied in two modifications of the same general character as hereinafter set forth but which modifications comprise substantially similar elements.

A meritorious feature is that the framework is designed to provide a structural supporting frame for a generally rectangular type of tent. The four corner assemblies are similar and are connected together by the cross frame members. The corner assemblies may be uncoupled from certain cross frame members so that they can be folded into a small space and packed for storage or shipment with the cross frame members that have been uncoupled therefrom. The entire framework may be packaged for storage or shipment in a relatively small space.

Other objects, advantages and meritorious features will more particularly appear from the following description, claims and accompanying drawings, wherein:

Fig. 1 is a schematic illustration of a framework embodying a preferred form of the invention;

Fig. 2 is an enlarged fragmentary elevation taken from the point of the arrow 2 shown in Fig. 1;

Fig. 3 is a fragmentary elevation taken from the point of the arrow 3 shown in Fig. 2;

2

Fig. 4 is a cross sectional view taken on the line 4—4 of Fig. 3;

Fig. 5 is an enlarged detail of the end of the ridge of the roof of the structure shown in Fig. 1;

Fig. 6 is a perspective of a fragment of an end of a modified form of the framework;

Fig. 7 is an enlarged plan view taken from the point of the arrow 7 in Fig. 6;

Fig. 8 is a cross sectional view taken on the line 8—8 of Fig. 7; and

Fig. 9 is an elevation partly in section taken from the point of the arrow 9 in Fig. 7.

The framework is shown as formed of metal and primarily metal tubes and in the structural assembly shown in Fig. 1 the framework is of a generally rectangular shape provided with four upright legs indicated by the numeral 10. These legs are connected together at their upper ends by side cross frame members 12 and end cross frame members 14. Roof frame members 16 extend upwardly angularly from the legs and from the cross frame members as shown in Fig. 1. The upper ends of these roof frame members 16 are connected to each other and connected together by a longitudinal ridge member 18 as shown in Figs. 1 and 5.

Each upper corner comprises a framework assembly. These framework assemblies are generally similar. As shown in Fig. 1 the two assemblies at each end are connected together by the end cross frame member 14. This cross frame member 14 comprises a relatively long intermediate portion 18 telescoped within a short end portion 20.

It may be secured therein by interlocked indentations 22 as shown in Fig. 2. There is rigidly secured to each end portion 20 linkage in the form of a pair of links 24. These two links 24 are disposed on opposite sides of the end section 20 and may be welded thereto as shown. These links project as shown particularly in Fig. 2 downwardly angularly away from the adjacent end portion 20 and outwardly toward the outer end thereof. They also project upwardly angularly away from the portion 20 and inwardly away from the adjacent end thereof. The leg member 10 is hinged between the downwardly projecting links upon a pin 26 which may be provided with a removable nut 28 as shown in Fig. 3. A bridge portion 30 extends between the two links as shown in Fig. 2. When the leg is unfolded from the cross frame member 18 to a position perpendicularly with respect thereto as shown in Fig. 2 the upper end of the leg abuts the bridge 30 and holds the leg in a position normal with respect to the cross member, all as shown in Figs. 1 and 2.

The roof member indicated generally as 16 also comprises an intermediate portion and end portions telescoped thereover and secured thereby. This roof member is hinged between the upwardly extending portion of the links 24 upon a pin 32. Such pin may be provided with a removable nut 34 as shown in Fig. 3. The end of the roof member 16 is turned over as at 36 as shown in Figs. 2 and 3 so that when the roof member is elevated to the provided angle with respect to the cross frame member this portion 36 engages the end of the cross frame member and determines the upward angle of the roof member, all as shown in Fig. 2.

The upper ends of the roof members 16 have their end portions flattened as shown in Fig. 5 and the outer ends of the ridge member 18 has its end portion flattened as shown in the same figure and such flattened end portions are detachably secured together by a bolt 38 provided with a removable nut 40 as shown in Fig. 5. It will be seen that the end cross frame members and the roof members and the ridge member are all built up out of intermediate portions and an end portion which are all telescoped thereover and this is for the purpose of convenience and attachment in a suitable manner as shown.

65

The construction disclosed in the first five figures also includes a support 42 in the form of an angle welded or otherwise fixed to the linkage 24 as shown in Figs. 3 and 4. This provides a stub-like projection adapted to be received within the end of the hollow tubular side frame member 12. The bolt 44 may be removably inserted therethrough as shown in Fig. 4. This bolt has a nut 46 thereon so that these side frame members may be detachably coupled with the support 42 or uncoupled therefrom as desired.

It will be seen that when the bolts 38 are removed from the opposite ends of the ridge member 18 and the roof frame members 16 are detached, the roof members 16 may be folded to lie substantially flat against the end cross frame member 14. The leg 10 may be folded upwardly against such cross frame member. Such cross frame member plus the leg plus the roof members may thereby be folded into a small package. This is true for each end of the structure. The two side frame members 12 and the ridge member 18 may be likewise collected and disposed in alignment. The legs may be suitably braced apart across the sides and across the ends adjacent to the bottom of the legs by any suitable cross frame members. On the other hand the legs may be sharpened so as to be driven in the ground if such method of securing is desired. The invention does not concern itself with this portion of the structure.

In the construction shown in Figs. 6 through 9 a slight modification is illustrated. The roof shown in Fig. 6 is what is called a "hip" roof. Generally the construction is similar but it differs in minor detail. It is understood that although the fragment illustrated in Fig. 6 is but one end of the structure, a structure similar generally to that of Fig. 1 is proposed and that the opposite end from that shown in Fig. 6 would be duplicated. In Fig. 6 the legs are indicated as 50, the end cross frame member as 52 and the side cross frame members as 54. The upright angular roof members are indicated by the numeral 56 and the ridge roof member by the numeral 58. The ridge member is adapted to be detachably coupled with the upper ends of the angular rafter-like room members 56 by having the flattened ends of the frame members detachably connected by a bolt 60 in a manner similar to that shown and described in the view of Fig. 5 of the first construction.

Opposite ends of the cross frame side members 54 are provided with corner assemblies as shown in Figs. 7, 8 and 9. To each end of the cross frame member 54 is fixed linkage 62 in the form of a pair of links welded or otherwise attached to opposite sides of the tubular section 54. This pair of links extends downwardly angularly with respect to the frame member 54 and toward the adjacent end thereof. The links are bridged together by a piece which is welded to the links and to the frame member 54. Between the outer ends of the link is swingably pivoted leg 50. It is pivoted thereto upon a pin 66 which is provided with a removable nut 68.

In the figures of the drawings the leg is shown as unfolded to a position substantially perpendicular with the respective cross members 52 and 54. In such position the upper end of the leg abuts the bridge member 64 so as to provide a limit for the unfolding member. The frame member 54 to which the linkage 62 is secured has a bracket support 70 welded or otherwise secured to one of the links and projecting perpendicularly with respect to leg 50 and the cross frame member 54. This bracket support is adapted to receive one end of the end frame member 52 as shown and to have a removable bolt 72 pass therethrough to secure the end frame member to the support.

The outer end of the cross frame member 54 has a bracket support 74 welded or otherwise secured thereto. The roof rafter frame member 56 is telescoped over this stub support 74 and held detachably thereto by a bolt 76 as shown in Figs. 1 and 7.

It is apparent that when the bolts 60 are removed from opposite ends of the ridge member 58, uncoupling the ridge member from the rafter members 56 and uncoupling such rafter members from each other and the bolts 76 are removed, uncoupling the lower ends of the rafter members from the supports 74 and the bolts 72 are removed, uncoupling the opposite ends of the cross frame members 52 from the corner assemblies, such ridge member, rafter members and end cross frame members may be assembled together and the legs 50 may be folded upwardly against the cross frame members 54 into substantial parallelism therewith and the entire structure assembled into a very small space. In each of the two structures shown the framework may be quickly disassembled and packaged together or it may be assembled in the upright position to receive a tent. As stated with respect to the construction disclosed in Figs. 1 through 5, the lower ends of the legs may have cross frame members extending therebetween and detachably connected therewith by bolts or the like in a conventional manner. The framework would therefore be braced so that it could be placed upright on the ground and occupy such position. Guide wires or cords might be extended from the tent to pegs in the ground if such were desired in the manner well known. On the other hand the legs might have their lower ends sharpened so as to be driven into the ground in much the same manner as tent stakes or upright supports.

What I claim is:

1. In a structural framework for a shelter, an upper corner assembly comprising, in combination, a cross frame member, a pair of parallel links fixed to opposite sides of the cross frame member adjacent to but spaced from one end thereof, said links having complementary end portions extending downwardly angularly away from the frame member toward its end and at an acute angle with respect to said end portion of the frame member, a leg member pivoted between the downwardly extending end of the portions of the links to be folded toward the cross frame member to a position of substantial parallelism therewith or to be unfolded away from the cross frame member to a position substantially normal thereto, a bridge portion extending between the links adapted to limit the unfolding of the leg member to a position substantially perpendicular with respect to the cross frame member, one of said links provided with a stub support projecting perpendicularly with respect to the link and substantially within the horizontal plane of the cross frame member and within the vertical plane of the leg member, and a frame member removably secured to said stub support as an extension thereof, said corner assembly having a roof member extending upwardly angularly therefrom at an acute angle with respect to the horizontal plane of the two frame members to support a ridge member of the framework.
2. In a structural framework for a shelter, an upper corner assembly comprising, in combination, a cross frame member, a pair of parallel links fixed to opposite sides of the cross frame member adjacent to but spaced from one end thereof, said links having complementary end portions extending downwardly angularly from the frame member toward said end thereof and at an acute angle with respect to said end portion of the frame member, the opposite complementary end portions of said links extending upwardly angularly from the cross frame member and away from said end thereof and at an obtuse angle with respect to said end portion of the frame member, a leg member pivoted between the downwardly extending end portions of said links to be folded toward the cross frame member to a position of substantial parallelism with respect thereto or to be unfolded away from the cross frame member to a position substantially perpendicular with respect thereto, a bridge portion extending between said links adapted to limit the unfolding of the leg member to a position substantially perpendicular with respect to the cross frame member, a roof member pivoted between the upwardly

extending end portions of the links to be folded toward the cross frame member substantially into parallelism therewith or to be unfolded away from the cross frame member to a position forming an acute angle with respect thereto, said roof member having its end adjacent to its pivot point bent toward the cross frame member and adapted to engage the end thereof to limit the unfolding of the roof member with respect to the cross frame member to an acute angle with respect thereto, one of said links provided with a stub support projecting perpendicularly with respect to the link and at a right angle with respect to said cross frame member and substantially within the horizontal plane thereof and within the vertical plane of the leg member, and a frame member removably secured to said stub support as an extension thereof.

3. In a structural framework for a shelter, an upper corner assembly comprising, in combination, a cross frame member, a pair of parallel links fixed to opposite sides of the cross frame member adjacent to but spaced from one end thereof, said links having complementary end portions extending downwardly angularly from the frame member toward its end and at an acute angle with respect to said end portion of the frame member, a leg member pivoted between the downwardly extending end portions of the links to be folded toward the cross frame

20
25

member to a position of substantial parallelism with respect thereto or to be unfolded away therefrom, a bridge portion extending between the links adapted to limit the unfolding of the leg member to a position substantially perpendicular with respect to the cross frame member, a bracket support secured to the end of the cross frame member and extending upwardly angularly at an acute angle with respect thereto, a roof member removably secured to said bracket support as a continuation thereof, a second bracket support secured to one of said links projecting perpendicularly with respect thereto and with respect to the vertical plane of the leg member and within the horizontal plane of the cross frame member and at a right angle with respect to said cross frame member, a second frame member adapted to be removably secured to said second bracket support as a continuation thereof to extend at a right angle with respect to the first mentioned cross frame member.
